Primary Examiner — Ian Simmons*Assistant Examiner* — Carissa C Fitts(74) *Attorney, Agent, or Firm* — Sterne, Kessler, Goldstein & Fox P.L.L.C.(57) **CLAIM**

The ornamental design for an inflatable solar-powered lantern, as shown and described.

DESCRIPTION

FIG. 1 is a front perspective view of an inflatable solar-powered lantern showing our new design;

FIG. 2 is a top view thereof;

FIG. 3 is a side view thereof; and,

FIG. 4 is a bottom view thereof.

The broken lines form no part of the claimed design.
